UNITED STATES PATENT OFFICE

JOHN DRIEDGER, OF VONDA, SASKATCHEWAN, CANADA

STOOKING MACHINE

Application filed September 18, 1930. Serial No. 432,725

This invention relates to improvements in stooking machines.

For a considerable period a great many stooking machines have been devised adapted to stook grain in the field but many disadvantages have been apparent in these attempted structures. Foremost among these disadvantages are bulkiness and the fact that in most cases these machines had to be operated as a separate unit requiring the attention of several field hands. In view of this these machines have proven very impracticable both from the point of operation and from the point of labour.

One of the main objects of the present invention is to overcome these disadvantages by providing a stooking machine which is comparatively simple in structure, although light and durable, and one which may be readily attached to a binder and operated simultaneously therewith.

A further object of the invention is to provide a machine of this character which will not require any extra horse power over that required for operating the binder.

A further object of the invention is to provide a novel and efficient form of stook receiving means operatively mounted on the frame at substantially one point which will quickly and efficiently deposit stocks on the ground.

A further object of the invention is to provide a machine practically automatic in operation throughout which may be quickly attached to the ordinary binder and merely requires the attention of the one man required to operate the binder.

A still further object of the invention is to provide a stooking mechanism which, by reason of its comparative simplicity, may be manufactured and placed on the market at a low figure.

With these and other objects in view the invention consists essentially of a portable framework having mounted thereon a supporting base or pedestal which rotatably supports a stook receiving basket. A conveyor is associated with the framework adjacent to and above the basket for depositing stocks therein and mechanism is asso-

ciated with the framework and related to the pedestal so as to automatically operate the basket to turn and tilt to deposit its load and to return the basket to normal position after unloading. A main operating lever and control member are provided for imparting the initial movement to the basket, as more fully described in the present specification and illustrated in the accompanying drawings which form part of the same.

In the drawings,

Figure 1 is an end elevation of the machine as a whole.

Figure 2 is a side elevation of Figure 1 taken on the conveyor side of the structure.

Figure 3 is a plan view of the machine.

Figure 4 is a side elevation of the machine illustrating the basket in dumping position.

Figure 5 is an enlarged plan view of part of the drive mechanism and mechanism for returning the basket to normal position.

Figure 6 is an enlarged detail elevation of Figure 5.

Figure 7 is an enlarged detail of the operating mechanism and pedestal for controlling the operation of the basket.

Figure 8 is a section on the line 8-8 of Figure 7.

Figure 9 is a section on the line 9-9 of Figure 8.

Figure 10 is an enlarged sectional detail of the trip mechanism for the control member.

Figure 11 is an enlarged front elevation detail of the clutch and gear shifting mechanism.

Figure 12 is a perspective view of the rack member for returning the basket to normal position.

Figure 13 is a sectional detail of the rod and spring connection on the conveyor drive mechanism.

Figure 14 is a side elevation partly in section of the sliding sleeve and locking bar associated with the cooperating latch.

Referring more particularly to the drawings 10 indicates the main framework constructed preferably of light angle iron section which is formed in substantially U-

shaped formation and provided with the rearward longitudinal extension 11. This frame is mounted on traction wheels 12 and 13 and the caster wheel 14 at the forward end of the frame.

5 The extension 11 is laterally bent as at 15 to provide the sub-framework 16 and the axle 17 of the traction wheel 12 is journalled between the extension 11 and the sub-frame 16. Above the sub-frame a raised framework 18 is mounted adapted to support a conveyor structure 19 for loading the sheaves into the basket, more fully referred to hereinafter.

10 The traction wheel 13 is mounted on the stub shaft 20 which extends through one side of the framework 10 and rigidly connects with the clamping bracket 21 disposed on the inside of the framework. A tiltable cross beam 22 is positioned between the sides of the frame 10 rigidly and adjustably fastened in the bracket 21 on the one side and correspondingly secured to a second bracket 23 (see Figure 3) on the opposite side, the bracket 23 being secured to, or preferably 25 integral with, a stub shaft 24 rotatably journalled in one side of the frame 10 and formed with a cranked end 25. Between the cranked end 25 of this stub shaft 24 and the sub-framework 16, a coil spring 26 is positioned to restrain the movement of the crank, which will be more fully referred to.

15 A supporting base or pedestal A is rigidly secured at 27 on the cross beam 22 towards one side thereof. This pedestal, is a salient feature of my invention and, as shown, is preferably in the form of a casting but of course might be constructed of other form, in accordance with requirements. The casting, as particularly shown, is designed to extend upwardly from the beam 22 in sloped relation thereto and is provided with a central bore as at 28 and with a longitudinally extending channel 29 intersecting the bore 28. Within the bore a hollow axle 30 is rigidly positioned, for instance by means of screw-threading 31. On the end of the casting or pedestal and over the outwardly extending end of the axle 30, a centrally bored, 20 rotatable disc member 32 is provided adapted to be secured on the axle 30, between the casting and a disc cap 33, retained by the axle 30, the disc 32 is readily rotatable about axle 30, between the two elements A and 33 25 with the provision of ball bearings 34 and 35 in suitable ball races on each side of the disc 32. A protruding bracket 36 is secured to one edge of the disc 32, although this is preferably formed integral therewith, and 30 an extension 37 protrudes from the diametrically opposite edge of the disc to the bracket 36.

The stoker basket B is directly secured to the bracket 36 at its rearward end and, 35 through the medium of a bracing rod 39

(Figures 2 and 8) rigidly and adjustably fastened to the extension 37, the forward end of the basket is braced to the disc so that on rotation of the disc 32, the basket will necessarily also rotate.

70 Around the exterior edge of the disc 32 a segmental crown gear 40 is rigidly fastened by means of a fastening screw 41 or the like (see Fig. 7). This segmental gear may be moved around the disc 32 by loosening the screw 41 so that the position of the teeth with respect to the disc may be changed to suit required operating conditions.

75 The basket B is a semi-frustro-conical form and comprises main semi-circular ribs 42 and 43 which are clamped to move with the disc 32 through the bracket 36 and the brace 39. These ribs are connected to form a unit through the outer bars 44 and intermediate cross bars 45. Intermediate the 80 lighter ribs 46 are provided between the ribs 42 and 43 which are fastened to the outer cross bars 44 and cross bars 45 so that a complete receiving basket is thereby formed.

85 On the rib 42 a plurality of projecting arms 47 are rigidly secured and from these arms at right angles thereto tines 48 are pivotally secured, the tines being restricted by the arms from moving from their right-90 angular position in one direction but may move in the opposite direction to a limited extent, their movement in this direction being controlled by a plurality of springs 49. These tines are designed to support the butts of sheaves deposited in the basket and steady 95 the stook thus formed, particularly in the discharging operation.

100 At the opposite end of the basket on the cross bars 45 depending sleeve members 50 are rigidly secured in any suitable manner 105 and these sleeves are adapted to slidably house the depending arms 51 of the semi-circular impelling member 52, the arms 51 being pivotally connected to this member as at 53. Coil springs 54 are anchored to the cross bars 45 and adapted to connect at their opposite ends with the extreme ends of the arms 51 (Fig. 1) so that these arms are thereby resiliently mounted on the frame 110 and are compressible along with the impelling member 52.

115 The impelling member is designed to be depressed by the sheaves falling in the basket but in unloading it will be seen that through the medium of coil springs 54 the impelling member will gradually be forced to its normal position extending out from the basket and therefore this impelling member will assist in shifting the formed stook from the basket in the discharging operation.

120 Co-operating with the impelling member are compressible arms 55 rotatably mounted on the outside cross bars 44 so that the cross bars form an axis about which the arms are 125 swung. Connected with these arms or

formed integral therewith are the operating lever arms 56.

Bracket posts 57 are rigidly mounted on the outside cross bars 44 adjacent to the arms 55 and, as illustrated in the drawings particularly Figure 3, these arms may take the form of a split skeleton structure adapted to connect with the cross bars 44 on each side of the mounting of the arms 55. On the outer end of the bracket posts 57 pulleys 58 are rotatably mounted. Cables 59 and 60 anchored at their extreme ends to the ends of the lever arms 56 extend over the pulleys 58 in the bracket posts 57 and are adapted to be threaded through a series of pulleys 61 and 62 mounted in opposed relation on each side of the basket frame. These cables connect with a main cable or chain 63 which in turn extends to a control member, more fully referred to hereinafter.

From this it will be seen that, on movement of the main cable 63, the cables 59 and 60 will be pulled simultaneously forward over the series of guide pulleys 61 and 62 and the pulley 58 in the bracket posts. Correspondingly the lever arms 56 will be pulled upwardly thereby turning the compressible arms 55 about their axes and in towards the interior of the basket. These arms, it will be noted, are curved and when they are turned inwardly as just described they will contact with the sheaves deposited in the basket and will tend to compress them and form a firm stool. At the same time they will hold the stool during the discharging operation until they are finally released. In order to return them to normal position after release, coil springs 64 are connected to the lever arms 56 and anchored to the intermediate cross bars 45 of the basket so that immediately on release the compressible arms 55 will be returned to normal position.

Within the outer end of the hollow axle 30 a collar 65 is mounted, the collar being formed with a bifurcated end 66 operatively carrying a pulley 67. The chain 63 is adapted to ride over the pulley 67 and extend down through the bore of the axle 30, extending under a pulley 68 positioned within the channel 29. In the forward part of the channel a carriage 69 is resiliently mounted on a coil spring or other resilient mounting 70 so that it may move vertically. The channel in this area is formed so as to provide a guide-way for the carriage 69 and, while allowing for vertical movement, will not permit of side play. A slot 71 is formed in the lower end of the carriage and a pulley 72 is operatively mounted therein over which the chain 63 passes to the forward end of the machine where it is anchored as at 73 to one part of a control member C.

The upper portion of the carriage is in the form of a latch member 74 protruding above the upper part of the pedestal, and

adapted to contact with a lug 75, which protrudes from the base of the bracket 36. This constitutes means for retaining the basket in normal position. It will be seen, of course, that on depression of the carriage 69 the latch member 74 will be moved downwardly out of engagement with the lug 75, and therefore the basket will be free to move in its normal course of travel.

The control member C is in the form of a disk 76, which is provided with peripheral gear teeth 77 and is adapted to be rotatably mounted between the arms 78. As shown in Figure 8, these arms protrude from the pedestal A, or could be attached to any other convenient part of the machine to support the control member in its mounting forwardly of the basket. A plate 79 is secured to the disk 76 on one side thereof, and a lever arm 80 is secured to the plate by means of a slot and bolt connection, such as 81, to provide for adjustment if necessary. The lever arm 80 is also provided with additional lugs 82 to provide for further adjustment. The plate 79 is flanged as at 79^a to form a guide or drum for winding the chain 63.

It will be seen that the control member C is adapted to rotate around its axle mounting 83 and between the arms 78. Adjacent to the end of the lever arm and on one side thereof a spring 84 is adapted to press an attached lug 85 through a slot formed in the end of the arm and thus provide a compressible latch member. On rotation of the control member C the lever arm 80 will turn therewith until it reaches a point between the arms 78. At this point a slot 86 is formed in one of the arms 78, and when the latch member or lug 85 comes into register with the slot 86 through the medium of the spring 84 this latch member will be pressed into the slot, thereby retaining the control member C in rigid locked position.

At the side of the slot 86 in one arm 78 a plunger member 87 is positioned adapted under certain conditions to protrude into the slot 86, and this plunger member is carried by a spring plate 88 secured to slotted arm 78. A resiliently mounted plate 89 is also mounted on the arm 78 through the medium of support 90 to form a bearing surface for coil spring 91, which is also mounted on the support 90 and extends in bearing engagement with the plate 89. To the free end of the coil spring a chain 93 is secured which is anchored as at 94 on part of the framework of the machine for a dual purpose more fully referred to hereinafter.

To effect operation of the various parts of the machine a bevel gear 95 is keyed on the shaft 17 adapted to mesh with a corresponding bevel gear 95^a mounted on the cross shaft 96. At the opposite end of the cross shaft a bevel gear 97 is positioned which meshes with the corresponding bevel gear 98 120

on the counter shaft 99. The counter shaft 99 extends transversely of the framework and is journalled in bearings 100 and 101 mounted on the frame 10 and on the cross brace 102, extending between adjacent sides of the frame 10. Towards one end of the counter shaft 99 a pair of opposed bevel gears 103 and 104 are mounted, which are adapted to alternately mesh with a bevel gear 105 carried on the end of an inclined shaft 106. The gears 103 and 104 are provided with clutch members 107 and 108 adapted to lock with corresponding clutch members 109 and 110, which are keyed on the shaft 99.

On the extremity of the shaft 99 a gear 111 is slidably keyed which is adapted to mesh with the peripheral gear teeth of the disc 76 in order to impart rotary motion to the control member C. On brace bar 112 extending between the cross brace 102 and the frame 10, or any other suitable mounting, a lever mounting 113 is rigidly secured which pivotally carries the main operating lever D. The operating lever is pivoted adjacent to the lower end thereof, forming a lower gear shifting portion 115 (see Fig. 11), which contacts with the gear shifting frame 116, slidably mounted on the shaft 99 and rigidly secured to the gear 111 so that when this lever is pushed in one direction the lower end will contact with the frame 116 and shift the gear 111 axially on the shaft into engagement with the gear teeth 77 of the disc 76. An arm 117 extends upwardly from the lever frame, and a dog 118 is pivotally mounted on this arm link-connecting through a link 119, the lower portion of the main operating lever 115 and the lower portion of the dog so that the upper portion of the dog is engaged with a clutch shifting frame 120 when the main operating lever is moved in one direction. The clutch member 110 is thus shifted into engagement with the clutch member 108 on the gear 104 so as to cause the gear 104 to rotate with the shaft 99. The clutch shifting frame 120 is braced from the shaft 99 through the bracing member 121, and this is in turn braced through a rod 122 rigidly fastened on one part of the frame. On the end of the clutch shifting frame 120 a lug 123, formed with a curved surface, is rigidly positioned and this is designed to shift the frame to engage the clutch member 107 with the clutch member 109 in a manner to be later described.

On the end of the shaft 106 a bevel gear 124 is mounted which is designed to mesh with a bevel gear 125 on the shaft 126 carried in the cross bearing 127. On the opposite end of the shaft 126 a second bevel gear 128 is mounted, which, during normal position of the basket, is designed to freely ro-

tate adjacent to the segmental crown gear 40, at a position as shown in Figure 7 just adjacent the teeth of this gear. However, this gear is designed to engage with the segmental crown gear to turn the basket 70 around the pedestal in unloading and return it for loading.

It will now be seen that on forward movement of the frame through the medium of the shaft 96, geared with the traction wheel 12, the shaft 99 will be caused to rotate. On pulling the operating lever in one direction the gear shifting frame 116 will move the gear 111 axially along the shaft 99 to engage with the teeth 77 of the control member C. At the same time through the medium of the link 119 the dog 118 will cause the clutch shifting frame 120 to engage clutch member 110 with clutch member 108, thereby causing rotation of the bevel gear 105 in one direction and consequently the bevel gear 128 through the medium of the shaft 106 and associated gears. However, as stated, the gear 128 is free from the segmental crown gear 40 and merely idles. The control member C will be caused to rotate through gear 111, correspondingly moving the attached lever 80 until the latch 85 registers with the slot 86 in one of the arms 78. At this point the lever arm will be locked in engagement with the arm 78, but during the turning movement the attached chain 63 will be pulled and wound around the flanged surface 79^a of the plate 79. On pulling this chain the 100 depressible arms 55 will operate as described. At the time the chain, on becoming taut, will depress the carriage 69 through the medium of the pulley 72, and thus withdraw the latch member 74 from engagement with the lug 75, leaving the basket free to rotate. At this point the basket will turn slightly due to the inclined position of the pedestal, and the teeth of the gear 128 will engage with the 110 teeth of the segmental crown gear 40 and thus rotate the basket about the pedestal.

Due to the inclined position of the pedestal the basket will assume substantially a vertical position instead of a horizontal position, (see Fig. 4) thus up-ending the stool carried therein, and when the basket has reached practically its full extent of travel, the rib 42 will contact with the curved plate 129 on the end of a trip lever 130 and consequently 115 depress it. At the end of the trip lever 130 a link 131 is pivotally secured. This link is also pivotally mounted as at 132 on the cross beam 21. A further connecting link 133 is pivoted to the link 131, and this in turn is pivoted to the slidable sleeve 134 of a locking bar 135. The locking bar is adapted to normally extend beneath a latch 136, which is forwardly sprung pressed by means of a spring 137. However, the movement of 120

the sliding sleeve 134 will depress the latch 136 and thus free the locking lever 135 permitting the cross beam 22 to turn about the stub axles 20 and 24 so that the pedestal and attached basket will swing downwardly to vertical position, the tines 48 resting on the ground, together with the butts of the sheaves. The chain 93 previously referred to will limit the extent to which the beam 22 will turn, and when it has reached the extent of travel will tighten. This will exert a pulling force on the coil spring 91, and through the medium of the plunger member 87 the latch 85 will be disengaged from the slot 86, and due to the influence of the coil spring 54 on the depressible arms 55 these arms will be caused to swing open, pulling on the chain 63, returning the control member C to normal position and releasing the stool. On the further forward motion of the machine, therefore, the stool will be deposited on the ground.

Rigidly mounted on the cross beam 22 as at 138 is a stopping member 139. This stop member is suitably curved or mounted in any suitable manner so that its outer end extends substantially parallel and adjacent to the trip 130 and the end of the stop member 139 is formed with a curved plate 140 of similar form to the plate 129 of the trip lever. A suitable guide 141 is secured to the stop member 139 adapted to embrace the trip lever 130 so as to eliminate side play in the movement of the trip lever. The rib 42 of the basket B is designed to contact with the end 140 of the stop member 139 after it has depressed the trip lever 130 and this finally arrests the turning movement of the basket.

As illustrated in Figure 7 the latch 136 is operatively mounted in a suitable bracket 142 and the sleeve 134 of the locking bar is slidably mounted on the locking bar and retained there by means of a pin 143 which operates with a longitudinally slot formed in the sliding sleeve 134. A cam member is provided on the latch 136 in the form of a lug 144 which, on sliding movement of the latch 136 under pressure of the sliding sleeve 134 contacts with the member 133 on the clutch shifting frame 120 so that the clutch member 109 is then engaged with the clutch member 107 and the clutch member 110 is disengaged from the clutch member 108 in this manner. The shaft 99 is therefore brought into driving engagement with the bevel gear 103 meshing with the bevel gear 105 and this provides for opposite rotation of the segmental crown gear 40 for turning the basket about the pedestal A at the appropriate time when the basket is being returned to normal position.

For returning the basket to normal position a gear 145 is mounted on the shaft 96 adapted to engage with the gear wheel 146 which is mounted on the stub shaft 147

operatively journaled on the frame 10. On the opposite end of this shaft a gear 148 is keyed to the shaft provided with a clutch member 149 co-operating with the sliding clutch member 150 which is slidably retained on the shaft. The gear 148 is designed to operatively mesh with the quadrant 151 rigidly carried by a bracket 152 secured to the bracket 123 on the cross beam 22, so that this quadrant will move with the beam 22. Also secured to the bracket 23 is a projecting resilient arm 153 extending upwardly from the beam beside the bracket 152. The outer end of this arm is twisted and provided with a deflecting member 154 which, on turning movement of the beam after release of the latch 136, is designed to contact with the end of the clutch member 150 so that this will deflect the clutch member 150 axially into engagement with the clutch member 149.

During the downward movement of the quadrant the gear 148 is loose on the shaft and permits this movement. However, with the throwing in of the clutch member 150 at the termination of the downward movement of the beam 22, the gear 148 is in operative driving engagement with the stub shaft 147 and it will be readily apparent that, on rotation of the stub shaft, the gear 148 will operate through the quadrant to return the beam 22 to its normal position. In other words, on continued forward movement of the frame, through the rotation of the shaft 96, the gear 145 will correspondingly operate the gear wheel 146 and through the quadrant 147 and gear 148 effect the return of the cross beam 22. At the same time, when the beam reaches its normal position again, a projection 155 on the quadrant will contact with the inner surface of the clutch member 150 and throw it out of engagement with the clutch member 149 so that this mechanism is returned to normal position ready for the next operation of this character.

When the beam 22 has been returned to position it is held there by means of the latch 136 and locking bar 135. Previous to this, however, the rib 42 of the basket B will in its turning movement contact with the arm 129 of the trip lever 130 to disengage the locking bar 135 from the latch 136, the sleeve 134 depressing this latch. With the depression of the latch at this point the cam surface of the lug 144 contacted with the surface of the lug 123 and through the medium of the clutch members 107 and 109 placed the bevel gear 103 in driving engagement with the shaft 99 so that on substantial completion of the return movement of the beam 22, the gear 128 will mesh with the segmental crown gear 40. Due to the fact that this gear 128 turns through gear 103, in the opposite direction to its direc-

tion of turning in the first instance, namely on the discharging of the basket, the basket will be rotated back in the opposite direction to normal position.

5 To co-operate with the operation of the basket mechanism the conveyor must function simultaneously. This is accomplished through a bevel gear 97 on the extreme end of the shaft 96 meshing with the bevel gear 107 on the vertical shaft 158. The bevel gear 157 is provided with a clutch 159 similar in form to the other clutches described. The shaft 158 is provided with a universal joint connection 160 so as to allow a certain 15 amount of play which is necessary in the operation of the conveyor. The shaft 158 is therefore a sectional shaft having an upper section 161 which is preferably compound in structure, that is, in the form of a 20 co-operating rod and sleeve, (see Fig. 13) so as to permit of extension of the shaft which is sometimes necessary. The bevel gear 162 is mounted on the rod of the extension 161 and meshes with a further bevel gear 163 on the conveyor drive shaft 164. This conveyor drive shaft is journalled on the conveyor frame 19 and the conveyor proper consists of associated shafts 165 and 166 carrying the chains 167 provided with 25 the pickup fingers 168, as more particularly 30 illustrated in Figure 1.

The shafts of the conveyor are journalled in the connecting links 169 extending between the posts 170 and in well known 35 manner the links 169 may be raised together with the shafts 164, 165 and 166 through the medium of slots 171 in the posts 170, thereby providing for the passage of sheaves of different sizes between the conveyor 40 frame and the conveyor proper. Of course the gear 162 is held in mesh with the gear 163 through a suitable bracket and should the shaft 164 be raised the meshing of these gears will not be effected. The rod of the 45 shaft section 161 will move in its sleeve to compensate for the raising action.

The clutch 159 on the shaft 158 may be operated through suitable well known mechanism and this clutch may be operated 50 should it be necessary to stop the operation of the conveyor. For instance, if the basket did not return to normal position in time to catch the next sheaf or sheaves being elevated in the conveyor, the operator would 55 merely have to disengage the clutch 154 thus stopping the conveyor mechanism until the basket returned when, of course, the shaft 158 would be thrown into operation again.

In general operation the machine travels 60 forwardly with the binder and sheaves are delivered from the binder deck, indicated by the letter E in Figure 1, upon the conveyor framework 19 whence they are elevated to drop into the basket B. As the 65 basket fills the impeller member 52 is de-

pressed to meet the framework of the basket. When a sufficient number of sheaves has been received in the basket the operator pulls the operating lever D, thus actuating the gear shifting frame 116 to mesh with the gear 110 with the peripheral teeth 77 of the control member 76. At the same time the operation of the lever D through the medium of the dog 118 shifts the clutch shifting frame 120 to engage the clutch member 110 with the clutch member 108 so as to impart rotation to the gear 128 through the medium of the associated mechanism such as the gear 104, shaft 106 and 126. However, the gear 128 merely idles until the operation of the control member has been completed.

The control member C rotates under power of the gear 111 and the lever arm 80 travelling with the control member C finally assumes a position between the arms 78 when the latch member 85 enters into the slot 86 in one of these arms thus locking the control member. At the same time the cam member 76^a contacts with the gear shifting frame 116 thereby disengaging the gear 110 from the control member C, the spring 116^a retaining frame 116 in disengaged position. However, with the operation of the control member to its locked position, the chain 63 is pulled and wound upon the flange 79^a of the plate 79 and this will depress the carriage 69 in addition to, through the medium of the cables 60 and 62, compressing the arms 55 on the basket to compress the sheaves in the basket and also hold the sheaves within the basket during the turning movement.

On depression of the carriage 69 the latch member 74 is disengaged from the lug 75 thus freeing the basket so that it may turn and, due to the sloping of the pedestal A, the basket B turns slightly, sufficiently to engage the gear 128 with the teeth of the segmental crown gear 40. The basket is therefore, through this engagement, turned about the pedestal A through the medium of the disc 32 to which the basket is attached and when it has made a complete turn and the basket is substantially at right angles to its normal position, (Fig. 4) the rib 42 contacts with the curved plate 129 of the trip lever 130 and depresses it, finally coming to rest when the rib contacts with the plate 140 of the stop 139. The basket is now substantially vertical and the tines 48 and butts of the sheaves are substantially parallel to the ground. At this point the trip lever 130 disengages the locking bar 135 from the latch 136 through the forward movement of the sliding sleeve 134 which depresses the latch and the beam 22 now free turns on the stub axles 20 and 24 to rest the butts of the sheaves and supporting tines on the ground.

A certain amount of the shock of this 130

- movement is absorbed through a coil spring 36 between the end of the beam and the sub-frame 16 while shock is also absorbed through the chain 92 and coil spring 88. 5 However, at the extreme position after tilting of the beam, the chain 92 is drawn taut since this limits the extent to which the beam 22 may move. The coil spring 88 therefore depresses the plate 89 thus causing 10 the plunger 87 to extend into the slot 86 in one of the arms 78 and disengaging the latch 85 from the slot thereby freeing the lever arm 80. The arms 55 on the basket therefore are released from engagement with the stook 15 due to the pulling force of the springs 64. This also exerts a pulling force on the chain 63 through the cables 59 and 60 so that the control member C is returned to normal position. 20 The machine continues its forward travel and the stook now free and assisted by the impelling member under pressure of the springs 54 discharges and the tines 48 are withdrawn from underneath the stook due 25 to the movement of the machine. Simultaneously with this operation, however, the clutch member 150, through the medium of the member deflecting 154, has been thrown into engagement with the clutch member 149. 30 Therefore through the forward movement of the machine the gear now in driving engagement with the stub shaft 147 meshes with the quadrant 151 which is rigidly attached to the beam 22 and this beam 35 is therefore rotated on the stub shafts 20 and 24 back to normal position when the locking bar 135 engages with the latch 136 and retains the beam in normal position. The projection 155 on the quadrant at this 40 point contacts with the inner side of the clutch member 150 and disengages it from the clutch member 149, thus leaving the gear 148 free for the next operation.
- As previously explained, when the basket 45 in its discharging movement contacts with the trip lever 130, through the sliding sleeve 134, the latch 136 is deflected and the cam surface of the lug 144 contacts with the corresponding surface of the lug 123 on the 50 clutch shifting frame 120 and the gear 103 is then in driving engagement with the shaft 99 while the gear 104 has been thrown out of driving engagement with this shaft. The shaft 106 therefore operates in the opposite direction correspondingly operating 55 the gear 128 in the opposite direction through the associated connections. Therefore, when the beam 22 just about reaches its normal position, the gear 128 operating 60 in the opposite direction meshes with the segmental crown gear 40 rotating the basket in the opposite direction to return it to normal position when one of the arms 47, as illustrated in Figure 8, contacts with an up-standing spring member 172 arresting the 65 turning movement of the basket. At the same time the lug 76 slides over the top of the latch 74 on the carriage 69 depressing it and again effecting locking engagement between the latch 74 and lug 75, as indicated in Figure 5, so that the basket is retained in normal position. The basket is then ready to receive a further load of sheaves.
- It will be apparent from the foregoing 70 that a comparatively simple stooking machine has been provided and that the framework of this stoker may be readily attached to the binder frame to operate therewith. From experience in constructing the machine it seems apparent that no additional 75 horse power will be required to operate the combined machines other than that required for operating the binder.
- Instead of providing a separate main traction wheel for the stoker frame it is 80 conceivable that the bull wheel of the binder may be employed to make a more compact machine and therefore the disclosure illustrating the drive directly from the frame should not be interpreted in a limiting sense. Of course it is understood that 85 connections may be introduced between the control lever D and the binder so that the binder operator who looks after the combined machines will readily control the operation of the stoker from his position on the binder and, due to the structure of the stoker and simple operation thereof, as described, it will be readily seen that this machine will only require the attention of the 90 binder operator so that additional labour in stooking is completely eliminated.
- Various modifications may be made in 95 this invention without departing from the spirit thereof or the scope of the claims, and therefore the exact forms shown are to 100 be taken as illustrative only and not in a limiting sense, and it is desired that only such limitations shall be placed thereon as are disclosed in the prior art or are set forth 105 in the accompanying claims.
- What I claim as my invention is:
1. A stooking machine comprising a portable frame, a pedestal mounted on the frame, a stook receiving basket rotatably mounted 110 on the pedestal, means on the frame for delivering sheaves to the basket to form a stook, means for rotating and tilting the basket to discharge the stook, and means for returning the basket to normal position. 115
2. A stooking machine comprising a portable frame, an inclined pedestal rigidly mounted on said frame, a stook receiving basket rotatably mounted on the pedestal and normally retained in substantially horizontal position, means on said frame for delivering sheaves to said basket to form a stook, means for rotating said basket on the pedestal to a substantially vertical position, means for tilting the basket to dis- 120

charge said formed stook, and means for returning the basket to normal position.

3. In a stooking machine, a portable frame, a tilttable beam carried by the frame and normally locked in rigid position on said frame, a supporting base carried by the beam, a stook receiving basket rotatably carried by the supporting base, means for delivering sheaves to the basket to form a stook, means for rotating the basket, means for releasing the beam to tilt the basket and discharge said formed stook, means for returning the beam to normal locked position on the frame, and co-operating means for returning the basket to normal position.

4. A stooking machine comprising a portable frame, a pedestal mounted on said frame, a stook receiving basket rotatably mounted on the pedestal and normally retained in substantially horizontal position, means on said frame for delivering sheaves to the basket to form a stook, a control member mounted on the frame adapted to control the movement of the basket, means for actuating the control member to release the basket, means for rotating said basket on the pedestal to a substantially vertical position, means for tilting the basket to discharge said formed stook, and means for returning the basket to normal position.

5. A stooking machine comprising a portable frame, a pedestal mounted on said frame, a stook receiving basket rotatably mounted on the pedestal and normally retained in substantially horizontal position, means on said frame for delivering sheaves to the basket to form a stook, a control member mounted on the frame adapted to control the movement of the basket, means for actuating the control member to release the basket, means for rotating said basket on the pedestal to a substantially vertical position, means on the basket operated by the control member for compressing and retaining the stook and for releasing said stook on discharge of the basket, means for tilting the basket to discharge said formed stook, and means for returning the basket to normal position.

6. A stooking machine comprising a portable frame, a tilttable beam carried by the frame and normally locked in rigid position on the frame, a stook receiving basket rotatably carried by the beam, means for delivering sheaves to the basket to form a stook, means for rotating the basket, means for releasing the beam to tilt the basket and discharge said formed stook, and means for progressively returning the beam and basket to normal position.

7. In a stooking machine the combination with a portable frame, of a pedestal rigidly secured thereon and adapted to rotatably support a stook receiving basket thereabove, and co-operating mechanism for

operating said basket to discharge stooks formed therein and to return the basket to a normal receiving position.

8. In a stooking machine, the combination with a portable frame, of a tilttable beam mounted on the frame and normally retained in locked position thereon, a pedestal rigidly secured on said frame adapted to rotatably support a stook receiving basket thereabove, and co-operating mechanism for rotating the basket and tilting the beam to discharge stooks formed therein and to return the beam and basket to normal position.

9. A stooking machine comprising a portable frame, a pedestal rigidly mounted on said frame, a stook receiving basket rotatably mounted on the pedestal and normally retained in substantially horizontal position, means on said frame for delivering sheaves to the basket to form a stook, a control member adapted to control the movement of the basket, means for rotating said basket on the pedestal to a substantially vertical position, a main operating lever adapted to set the control member and rotating means into operation, means for automatically tilting the basket to discharge the formed stook on rotation of the basket, and means for returning the basket to normal position.

10. A stooking machine comprising a portable frame, a pedestal mounted on the frame, a stook receiving basket rotatably mounted on the pedestal, means on the frame for delivering sheaves to the basket to form a stook, a control member for controlling the operation of the basket, means on the basket operable through the control member for compressing and retaining said stook during the discharging of the basket, means for rotating and tilting the basket to discharge the stook, means for returning the basket to normal position, and means for automatically returning the control member to normal position on a discharging operation of the basket whereby said compressing means is actuated to release the stook.

11. In a stooking machine including a portable frame and a stook receiving basket rotatably mounted thereon, a control member for controlling the operation of the basket comprising a rotatable disc, a flexible cable anchored on the disc and designed to operate stook compressing means and a basket retaining latch, a drum member formed on the control member for winding the cable during operation, and means for rotating the control member.

12. In a stooking machine, a portable frame, a tilttable beam carried by the frame and normally locked in rigid position on said frame, a supporting pedestal carried by the beam, a stook receiving basket rotatably carried by the pedestal, means for deliver-

ing sheaves to the basket to form a stook, means for rotating the basket, means for automatically releasing the beam to tilt the basket, on rotation thereof, means for compressing and retaining the stook in the basket during rotation thereof, means for automatically releasing said compressing means on tilting of the beam to discharge the stook, means for returning the beam to 10 normal locked position on the frame, and co-operating means for returning the basket to normal position.

13. The device as claimed in claim 12 in which the means for tilting the beam comprises a trip latch mounted on the frame and releasable through contact with the basket during rotation.

14. The device as claimed in claim 12 in which the means for returning the beam to 20 normal position comprises a gear on the frame, a quadrant on the beam meshing with the gear, said gear being provided with a clutch, and means are provided for automatically throwing the clutch into and out 25 of gear.

15. The device as claimed in claim 12 in which an impelling member is resiliently mounted in the basket adapted to assist in the discharge of the stook.

16. In a stooking machine provided with a stook receiving basket and associated mechanism for delivering sheaves thereto and for rotating and discharging the basket, a mounting for the basket comprising an inclined pedestal in the form of a bored casting having a channel intersecting the bore, a hollow axle rigidly secured in the bore, a rotatable disc member on the casting adapted to rotate about the axle, a cap rigidly secured on the hollow axle above the disc to retain said disc in rotatably mounted position, means associated with the disc to provide for rotation thereof, and means for rigidly securing the basket to the disc to 45 rotate therewith.

17. The device as claimed in claim 16 in which the means for providing for rotation of the disc consists of a segmental crown gear adapted to be adjustably secured to the disc.

18. The device as claimed in claim 12 in which means for automatically releasing said compressing means on the tilting of the beam comprise a control member rotatably 55 mounted on the frame and connected to the compressing means through the medium of a main cable, co-operating means between the control member and the frame for locking the control member in a predetermined 60 position, and a resilient plate and plunger operated by a coil spring carried on the frame and tensioned on tilting of the basket for releasing the basket from locked position.

19. A stooking machine comprising a port-

able frame mounted on traction wheels including a main traction wheel, a drive shaft carried by the frame and rotated by the main traction wheel, a tiltable beam carried by the frame and normally locked in rigid position on said frame, an inclined pedestal rigidly carried by the beam, a stook receiving basket rotatably carried by the pedestal, means for delivering sheaves to the basket to form a stook, a control member mounted on the frame adapted to control the movement of the basket, means for actuating the control member to release the basket, means for rotating said basket on the pedestal, means on the basket operated by the control member for compressing and retaining the stook and for releasing said stook on discharge of the basket, a trip latch on the frame operated by the basket on rotation thereof for unlocking the beam to effect tilting thereof, a resilient impeller member in the basket for assisting in discharge of the stook, means for returning the beam to normal locked position on the frame, and co-operating means for returning the basket to normal position, said means for actuating the control member, rotating the basket and returning the beam to normal position being driven by said drive shaft.

20. The device as claimed in claim 19 in which the means for delivering sheaves to the basket comprise a raised conveyor framework, a conveyor in the form of a chain pickup member rotatably mounted on the conveyor framework and discharging above the basket, said conveyor framework being adapted to receive sheaves from a binder deck, the conveyor being operatively driven from the drive shaft, with the provision of means for throwing the conveyor out of operation.

In witness whereof I have hereunto set my hand.

JOHN DRIEDGER.
